Primary Examiner — Marie D. Fast Horse

(57) **CLAIM**

The ornamental design for an intelligent cash register, as shown and described.

DESCRIPTION

1. Intelligent cash register
2. Portion of intelligent cash register

- 1.1 : Front
- 1.2 : Back
- 1.3 : Left
- 1.4 : Right
- 1.5 : Bottom
- 1.6 : Top
- 1.7 : Perspective
- 2.1 : Front
- 2.2 : Back
- 2.3 : Left
- 2.4 : Right
- 2.5 : Bottom
- 2.6 : Top
- 2.7 : Perspective

These designs are for an intelligent cash register that is used for cash registering; design 2 is the basic design; the key design point of design 1 lies in the shape of the product, and the reproduction that can best show the key design point is the perspective view of design 1.

1 Claim, 14 Drawing Sheets
